UNITED STATES PATENT OFFICE.

JOHN W. D. FIFIELD, OF NORTH BROOKFIELD, ASSIGNOR TO ALFRED H. BATCHELLER, OF BOSTON, MASSACHUSETTS.

LAST OR HOLDER FOR LASTING BOOTS OR SHOES.

SPECIFICATION forming part of Letters Patent No. 296,154, dated April 1, 1884.

Application filed December 11, 1883. (No model.)

To all whom it may concern:

Be it known that I, JOHN W. D. FIFIELD, of North Brookfield, county of Worcester, State of Massachusetts, have invented an Improvement in Lasts or Holders for Lasting Boots or Shoes, of which the following description, in connection with the accompanying drawings, is a specification, like letters on the drawings representing like parts.

10 This invention has for its object the production of a last more especially adapted to retain the crimped instep-covering portion of the front or vamp of a boot or shoe in its crimped shape while being lasted. Crimping the front or vamp about a shoe stretches and curves it to properly fit the top or highest part of the foot; but when lasting such crimped front or vamp the closed upper is frequently so drawn upon the last and across the upper end of the 15 block of the last as to contract the parts previously stretched by crimping. To obviate improper contraction of the upper above the ankle-joint or across the top of the foot when lasting the upper, I have provided the last-block with an ankle-holding extension, herein shown as a loop or eye, extended back to the heel of the last, and adapted to fit over the last-holding standard.

20 My invention consists, essentially, in a last having a block provided with an ankle-holding extension or prolongation, substantially as will be hereinafter described and represented.

25 Figure 1 represents the upper or block side of my improved last; Fig. 2, a like view, but with the block removed; and Fig. 3 represents one of my improved lasts in section, but applied to a standard, which serves the purpose of keeping the last and its block in proper position with relation to each other with the 30 bottom of the last uppermost, the position it should occupy to have a front or vamp drawn over it in lasting or when securing the sole.

35 My improved last is made in two parts, and preferably of cast metal.

40 In the drawings, A is the body of the last, and B the block. The end of the block nearest the toe of the last is provided with a tongue, b, to enter a recess formed in the body of the last. The upper end of the block, instead of

45 terminating substantially at the line $x^2 x^2$, is 50 prolonged or extended to form an ankle extension or portion, b^2 , which will preferably be extended rearward, as at b^3 , across the neck a^2 of the body of the last, to form an extension for it, as best shown in Fig. 3. The part b^3 of 55 the block is herein shown as an eye or loop, and at its outer end is a lug, c, which enters a recess, c^2 , in the neck of the last, (see Fig. 2,) such lug and projection retaining that end of the block and last from lateral movement the 60 one of the other. The last-body is provided with an inwardly-curved locking-shoulder, d, and the inner side of the part b^3 is curved to accord with the same, and both are grasped by the concaved part of the last-standard G, be- 65 tween the projection e f, they forming a hook to grasp and hold the last and its block. The opposite side of the standard G is convexed at h to co-operate with a concaved part of the block. Pressure upon the bottom of the last 70 with the parts in the position Fig. 3, tends to bind the last and its block together, and the extension b^2 of the block keeps the upper out at the ankle or junction of the foot and leg covering parts of the boot or shoe, and when 75 the block is to be withdrawn, its removal is not, as with the common last-block, retarded or resisted by the binding of the leather across its top.

80 In lasting a crimped boot or shoe upper on an ordinary backward movement or sliding of the block of the last causes the upper drawn about the same to be improperly contracted. The shoe or boot having been lasted and the shoe nailed or pegged in place, the operator 85 will lift the last from the standard and remove the block B, and then again apply the last to the standard, to hold it while the boot or shoe is pulled off the said last, the hook e of the last holding down the heel of the last while the 90 projection e' rests on the inclined or curved back of the standard, as in Fig. 3.

I claim—

1. The body A of the last, combined with a last-block provided with an extension, b^2 , as 95 and for the purposes set forth.
2. The body A of the last, combined with a removable last-block provided with a back-

ward extension, b^3 , to cover the neck a^3 of the body of the last and prolong the same, substantially as set forth.

3. The body A of the last, combined with the 5 last-block provided with the extension b^3 in loop form, to receive between it a standard, substantially as described.

4. The body A of the last, provided at its rear end with a recess, c^2 , combined with the 10 last-block provided at its outer end with a lug, c , to enter the said recess, substantially as described.

5. The standard G, provided with the hook

e , combined with the last having a recess to be engaged by the said projection and with a 15 projection, e^3 , to bear upon the standard at its side opposite the said hook, to hold the last while the boot or shoe is pulled from it, substantially as described.

In testimony whereof I have signed my name 20 to this specification in the presence of two subscribing witnesses.

JOHN W. D. FIFIELD.
